PAGE END LOCKING DEVICE FOR
TYPEWRITER PLATENS

Patrick J. Casey, Washington, D. C.

Application October 23, 1947, Serial No. 781,593

4 Claims. (Cl. 197—141)

1

This invention relates to an attachment for typewriters, and more particularly to an attachment for controlling the operation of the typewriter platen to determine with accuracy the width of the bottom margin of the typewritten page.

An object of the invention is to provide a device of the character indicated which will accurately control a predetermined period of rotation for the typewriter platen by means of which the number of typewritten lines on a page can be accurately limited.

A further object of the invention is to provide a device of the character indicated in which the selective adjustment of the device for the limiting of the platen movement to variable numbers of lines, is greatly simplified and capable of accurate control by the operator.

Various other objects will more particularly appear in the course of the following detailed description.

The invention consists in the novel construction, arrangement and combinations of parts hereinafter more particularly described and claimed.

One sheet of drawings largely diagrammatic, accompanies this specification as part thereof, in which like reference characters indicate like parts throughout.

In the drawings:

Figure 1 is a fragmentary perspective view of a portion of a typewriter showing the application thereto of the present invention;

Figure 2 is a transverse vertical cross section taken substantially on line 2—2 of Figure 1;

Figure 3 is an end view of a portion of the typewriter showing the application of the invention thereto, and

Figure 4 is a detail perspective of the stop arm. In the embodiment of the invention illustrated in the drawings, a typewriter frame is illustrated generally by T, and the conventional typewriter platen by P.

To control the number of rotations of the platen P and thereby the number of typewritten lines on the page, gears 1—1 are associated with the ends of the platen P, which gears mesh with gears 3—3 formed on or secured to the ends of a fluted shaft 2, the ends of which are journaled in the platen carriage 35 parallel with the shaft of the platen. The fluted shaft 2 is co-extensive in length with the platen P and arranged parallel with and spaced therefrom.

The fluted shaft 2 is engaged with a gear 5 upon which it is slidable, the gear 5 being secured on a

2

shaft 4 extending transversely of the typewriter frame and journaled thereon. One end of the shaft 4 carries a gear 6 which meshes with a gear 7, which gear 7 is formed with an axially positioned internally fluted bore 8 adapted to slidably receive and mesh with a clutch gear 9 mounted on a shaft 10, one end of which is journaled on the typewriter frame.

A disk 12 is provided formed with a plurality of circumferentially spaced transverse orifices adapted to receive a plurality of transversely disposed headed pins 24. The disk 12 is further formed with axially disposed bosses 13 and 14. The boss 14 is formed on its outer end with a hand knob 15 by means of which the disk 12 can be rotated, while the boss 13 is formed with an axially disposed internally fluted bore 17 adapted to slidably receive and mesh with the clutch gear 9. The shaft 10 of the clutch gear 9 extends in axial alignment through the bosses 13 and 14 of the disk 12 and is formed on its outer end with a finger plunger 11 between which and the inner end of the bore 16 formed in boss 14 is disposed a compression spring 34 tending normally to force shaft 10 and clutch gear 9 into the position illustrated in Figure 2 in which it is in engagement with and interlocks disk 12 with gear 7. It will be apparent that by pressure upon the plunger end 11 of shaft 10 the clutch gear 9 can be forced inwardly so as to disengage clutch gear 9 from the fluted bore of disk 12, thus permitting the free rotation of disk 12 by means of the hand knob 15 independently of gear 7.

A second disk 20 formed with a second set of circumferentially spaced orifices complementary to those in the disk 12, is provided, this disk 20 being formed with a boss 21 adapted to seat on the boss 14 of disk 12 and provided on its outer end with a hand wheel 23 by means of which the disk 20 can be moved axially with respect to disk 12. The boss 21 of disk 20 is journaled as at 22 in the typewriter frame, and thus supports the outer end of the associated disks and gear 7. The headed pins 24 are provided one for each of the aligned circumferentially spaced holes provided in disks 12 and 20, the heads of these pins being positioned outwardly with respect to disk 20 so that by withdrawing disk 20 axially to the left with respect to disk 12, all of the headed pins are withdrawn a substantial distance. A journal 28 is provided in the typewriter frame radially with respect to the axis of the disks and gear 7, and positioned so that a plunger 29 mounted therein is arranged to contact one of the headed pins in alignment therewith. The plunger 29 is formed

on its outer end with a finger button 32 and is normally held in retracted position as by compression spring 33 positioned between the finger button 32 and the journal 28.

A stop 27 is rotatably mounted on the inner end of rod 26 and arranged in position to be engaged by any of the pins 24 which are projected sufficiently to engage therewith. The rod 26 is non-rotatably but slidably mounted in a journal 25 in the typewriter frame, and has formed or secured on its outer end a finger button 30 between which finger button 30 and the journal 25 is positioned a compression spring 31 adapted to normally maintain the rod 26 in its outward position, in which position the stop 27 is in proper alignment to engage the inner end of any of the pins 24 that has been projected its full length through the associated disks 12 and 20.

The rod 26 and stop 27 are resiliently connected as by spring 40 and are further provided with intersecting pins 41 and 42 extending from said members respectively, whereby rotation of the platen in the normal direction of feed is arrested by engagement of a pin with this stop, but rotation of the platen in the opposite direction is permitted to the extent of a complete rotation of stop 27 on rod 26.

In order to adjust the device without reference to a particular sheet of paper, a window 37 is preferably cut from the end of the typewriter frame in position to expose to view one of the headed ends of the pins 24, and the said headed ends of said pins may be conventionally marked with suitable indicia to indicate lines or groups of lines advanced by rotation of the plate P.

To set the attachment to control the number of lines to be written on a particular sheet, the hand wheel 15 will be drawn outwardly, thereby retracting all of the headed pins 24 to the maximum distance to the left, thereby withdrawing the inner ends of all of said pins from the path of the stop 27. Thereafter, the disks 12 and 20 can be rotated by hand wheel 15 until the head of the pin bearing the indicia indicating the desired number of lines, appears through the window 37, at which point plunger 29 will be forced inwardly by pressure upon finger piece 32, thereby projecting the particular headed pin then in alignment with said plunger to its full length, thereby bringing the end of that particular pin into the path of the stop 27. Thereafter, rotation of the platen P will transmit rotary motion to the fluted shaft 2 and through gear 5, shaft 4, and gear 6, to gear 7, which will in turn transmit rotary motion through clutch gear 9 to disk 12 until the particular headed pin 24 which has been positioned by plunger 29 comes in contact with stop 27, which will lock the platen P against further rotation.

If at this point it is desired to complete a sentence on that page, the operator can by depressing finger button 30 remove stop 27 momentarily while the additional line or lines are typed.

It will thus be apparent that the platen will be accurately controlled yet with a possible flexibility as determined by the wishes of the operator.

Having thus described the invention, I claim:

1. A control device for a typewriter platen comprising a gear mounted on the frame of the typewriter, means for transmitting rotary motion from the platen to said gear, a disk coaxially mounted with said gear and formed with a plu-

rality of circumferentially spaced orifices, pins slidably positioned in said orifices parallel with the axis of the disk, clutch means associating the disk and gear, a stop positioned adjacent the disk and in a plane intersected by any pin projected sufficiently through the disk, means for simultaneously withdrawing all of the pins beyond the plane of the stop, and means for projecting a selected pin to intersect said plane.

2. The device of claim 1, with means for manually shifting the stop to a position clear of all of the pins.

3. The device of claim 1 in which the means for transmitting rotary motion from the platen to the principal gear includes a gear mounted at one end of the platen and coaxial therewith, a fluted shaft rotatably mounted in bearings carried by the platen carriage, said shaft arranged parallel with and spaced from the platen and in gear with the gear carried by the platen, and a second gear mounted medially of the typewriter frame in slidable and rotary engagement with the fluted shaft, said second gear mounted on a shaft geared to the principal gear.

4. A typewriter platen control device comprising a gear having a fluted axial bore, means for transmitting rotary motion from the platen to said gear including a fluted shaft carried by the platen carriage parallel with the platen, said fluted shaft slidably meshed with a gear mounted on a shaft carried by the typewriter frame, with gears connecting the platen with said fluted shaft and the second mentioned shaft with the first mentioned gear, a clutch gear slidably mounted in the fluted axial bore of said first mentioned gear, a disk having oppositely disposed axial bosses and an axially disposed bore, said disk formed with a plurality of circumferentially spaced transverse orifices, the axial bore of said disk enlarged and internally fluted to slidably receive the clutch gear in one boss, said clutch gear mounted on a shaft extending through said axial bore of the disk and journaled by one end on the typewriter frame, spring means normally biasing said shaft and clutch gear into a position interengaging both the first mentioned gear and said disk, a second disk formed with complementary transverse openings to those in the first disk, said second disk formed with an axial boss journaled exteriorly on the typewriter frame and rotatably mounted on a boss of the first mentioned disk, a spring biased plunger slidably mounted on the typewriter frame in alignment with the circumferentially spaced orifices in said disks, headed pins passing through the orifices in said disks, and a spring biased stop member normally positioned in the path of the end of any of said pins when said pin has been projected by said plunger the maximum extent through said disks.
